UNITED STATES PATENT OFFICE.

DECATUR H. HIBBERT, OF WALLINGFORD, PENNSYLVANIA.

HOUSE.

SPECIFICATION forming part of Letters Patent No. 531,032, dated December 18, 1894.

Application filed October 24, 1894. Serial No. 526,786. (No model.)

To all whom it may concern:

Be it known that I, DECATUR H. HIBBERT, a citizen of the United States, residing at Wallingford, county of Delaware, and State 5 of Pennsylvania, have invented a new and useful Improvement in Houses, of which the following is a full, clear, and exact description, reference being had to the accompanying drawings, which form a part of this specification.

My invention has for its object a novel construction whereby on a comparatively narrow frontage upon a street a wide front of house is obtained, and also consists in novel internal 15 arrangements in connection with this construction.

My improvement is especially applicable to houses which are to be constructed on the corners of streets, all of which will be more 20 clearly shown in the drawings, which illustrate an embodiment of my invention.

In the drawings—Figure 1 is a cellar plan view of my improved construction. Fig. 2 is a plan view of the first story, and Fig. 3 a 25 plan view of the second story.

The main walls of the house, as will be clearly seen, on two of the sides, to wit: the sides marked A and B, are, as in the ordinary house, usually at right angles to each other, 30 while the walls marked C and D in my construction have the wall E in common, said wall E making an oblique angle with each of the walls C and D. By this means, a front is obtained from the point e to the point f, the 35 front being partially upon one street and partially upon the other, and being of greater length than if the walls C were extended until they met, the streets being parallel, respectively, with walls C and D. The point 40 where the wall E commences on the wall C and ends on the wall D may be varied.

In Fig. 2, which shows the first floor plan, the central portion of the house is formed into a library which extends vertically up above 45 the second floor, and is provided at the level of the second floor with a balcony or portion projecting over a portion of the space of the said room so as to form practically a balcony around said library portion, having openings 50 from said balcony into the various rooms, thereby forming a passage to the several rooms, and providing a library with a lofty

or high ceiling, (see Fig. 3;) but the essential feature of my invention consists in forming a portion of the main or foundation walls of 55 the house at right angles to each other, and having a wall common to the walls of two sides and forming an oblique angle with each of said walls; and further, in forming in said angular portion a room which extends vertically above the second floor and is provided with a surrounding balcony at the level of 60 the second floor, having openings therefrom into the various chambers.

In the various drawings, I have shown different floors divided up into various rooms, although I do not by any means intend to limit myself to the particular formation of the rooms, except as will hereinafter be specifically claimed; but to particularize, as 65 shown in the drawings, thus, in Fig. 1, which is the cellar plan, 1 is a rear cellar; 2, a refrigerator; 3, the laundry; 4, brick walls; and on Fig. 2, 5 is the dining room; 6, the kitchen; 7, the parlor; 8, the passage; 9, the hall; 10, 70 the library, and 11, a partially covered porch; and in Fig. 3, 12, 13, 14 and 15 are chambers, 75 16 is the open space above the library, and 17 the balcony, having openings therefrom into the various rooms, which are clearly indicated in the drawings.

Having now fully described my invention, what I claim, and desire to protect by Letters Patent, is—

A new and improved construction of house 85 having two foundation walls at substantially right angles to each other, and two other foundation walls intersecting said last mentioned walls and extending a part of the distance of 90 the width and length of the house and connected by a wall making an oblique angle with the two last mentioned walls, and provided with a room, in the portion formed by the last mentioned wall, which extends vertically above the second floor, and provided 95 with an internal gallery at or about the level of the second floor.

In testimony of which invention I have hereunto set my hand.

DECATUR H. HIBBERT.

Witnesses:

FRANK S. BUSSE,
PHILIP BOUTELJE.
